US00D793720S

(12) United States Design Patent (10) Patent No.: US D793,720 S
(45) Date of Patent: * Aug. 8, 2017

(54) HALF ZIPPER BAG

(71) Applicant: Spencer Tien, Irwindale, CA (US)

(72) Inventor: Spencer Tien, Irwindale, CA (US)

() Term: 15 Years

(21) Appl. No.: 29/570,394

(22) Filed: Jul. 7, 2016

(51) LOC (10) Cl. 03-01

(52) U.S. Cl.

USPC D3/226

(58) Field of Classification Search

USPC D3/100, 104, 105, 106, 213, 214, 215, D3/218, 219, 224, 226, 232, 243, 247, D3/248, 265, 266, 267, 268; 150/106, 150/117, 118, 139, 143; 206/5, 5.1, 206/316.1, 545; D2/630; 248/902; 224/148, 205, 918, 919, 224, 226, 227, 224/236, 240, 242, 245, 247, 248, 250, 224/151, 252, 253, 662, 664, 665, 679, 224/271, 681, 904, 907, 911

(57) CLAIM

The ornamental design for a half zipper bag, as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view; and,

FIG. 7 is a bottom view.

The broken lines in the drawings are used to illustrate unclaimed portions and form no part of the claimed design. Dotted lines seen in FIGS. 1 and 3 are used to illustrate stitching that does not form a part of the claimed design.

1 Claim, 6 Drawing Sheets
